UNITED STATES PATENT OFFICE

PERRY P. YOHE AND WEBSTER CHRISTIE, OF WINDOM, MINNESOTA, ASSIGNEES, BY DIRECT AND MESNE ASSIGNMENTS, TO KOEHRING COMPANY, OF MILWAUKEE, WISCONSIN, A CORPORATION OF WISCONSIN

TIMING DEVICE

Application filed October 9, 1926. Serial No. 140,551.

Our invention relates to a mechanical timing device intended for general use but especially adapted for use in connection with a concrete mixing machine for timing the mixing of a batch of concrete. It is a well known fact in engineering that the strength of concrete depends a great deal on the proper mixing of the ingredients, and that all batches in a given job should be alike in order to 10 secure uniform strength, and time required in making a mixture of a given strength is also well known. There is a tendency, however, on the part of contractors to slight the proper timing of the mixing of concrete in 15 order to speed up the pouring of the same.

By the use of our invention, a batch of concrete will be mixed a predetermined length of time, in accordance with specifications, and then automatically dumped. As the mechanical timer cannot be tampered with, all batches will be alike and the poured concrete, when set, will have a uniform strength.

In the accompanying drawings, which illustrate the invention, like characters indicate like parts throughout the several views.

Referring to the drawings:

Fig. 1 is an end view of a concrete mixing machine having the invention embodied therein;

Fig. 2 is a side elevation of the machine as shown in Fig. 1;

Fig. 3 is a fragmentary plan view of the timing device on an enlarged scale;

Fig. 4 is a view partly in elevation and partly in vertical section taken on the line 4-4 of Fig. 3;

Fig. 5 is a detail view partly in elevation and partly in vertical section taken on the line 5-5 of Fig. 4;

Fig. 6 is a detail view with some parts sectioned on the line 6-6 of Fig. 4; and

Fig. 7 is a detail view in section taken on the line 7-7 of Fig. 2.

The concrete mixer illustrated is of the tilting drum type and of the parts thereof it is important to note the drum 8 mounted on the transverse portion of a U-shaped bar 9 to rotate on an inclined axis, as shown by full lines in Fig. 1. On the arms of the bar 9 are trunnions 10 and 11 journaled in bear-

ings on a frame 12 mounted on a four-wheeled truck 13. The drum 8 is held in its dumping position, as indicated by dotted lines in Fig. 1, by a gravity-held latch lever 14 which rests in a lock notch 15 in one of the flanges of a wheel 16 on the trunnion 11 and having a channel periphery.

The loading position of the drum 8 is indicated by full lines in Fig. 2, and to raise said drum from its dumping position, we provide a weight 17 attached to the wheel 16 by a cable 18 which runs over a guide sheave 19 on the frame 12 and arranged to be wound on said wheel during the dumping movement of the drum 8. The latch lever 14 extends transversely of the wheel 16, and when out of the lock notch 15, rides on the respective flange of the wheel 16 and automatically drops into said notch when brought into registration therewith under the rotation of the wheel 16.

The drum 8 is rotated on its oblique axis by an internal combustion engine mounted in a housing 13' on the truck 13, and only the driving shaft 20 of said engine is shown. The driving connections from the engine shaft 20 to the drum 8 includes a pair of axially aligned shafts 21 and 22, the former of which is journaled in a bearing on the frame 12, and the latter of which is journaled in part in a bearing on said frame and in part in a socket in the adjacent end of the shaft 21.

A clutch 23 is provided for connecting and disconnecting the shaft 22 to the shaft 21, at will. One member of the clutch 23 is keyed to the shaft 21 and the other member thereof is keyed to the shaft 22 for sliding movement. The sliding member of the clutch 23 is provided with a shipper collar 24 to which may be applied a shipper lever, not shown.

The shaft 21 is driven from the engine shaft 20 by a sprocket chain 25 which runs over a relatively small sprocket wheel 26 on said engine shaft and a relatively large sprocket wheel 27 on the shaft 21. On the inner end of the shaft 22 is a bevel pinion 28 which meshes with a ring gear 29 on the drum 8.

The machine is provided with a skip 30, adapted to receive given quantities of sand 100

and cement for a batch of concrete and then elevate and dump the same into the drum 8. Said skip is provided with upper and lower pairs of wheels 31 and 32, respectively, arranged to run on inclined track rails 33 on the truck 13. At the upper and lower ends of the rails 33 are pockets 34, the latter of which are arranged to receive the lower pair of wheels 32 and limit the downward movement of the skip 30. The upper pockets 34 are arranged to receive the upper pair of wheels 31 and cause the dumping action of the skip 30. A pair of cables 35 have one of their ends attached to the lower outer corners of the skip 30 and their other ends attached to a pair of drums 36 and arranged to be wound thereon. The drums 36 are keyed to a shaft 37 journaled in bearings on the frame 12. Also keyed to the shaft 37 is a pulley 38 driven from the engine shaft 20 by suitable connections, not shown.

On top of the frame 12 is a water tank 39 having a discharge neck 40 arranged to deliver a given quantity of water into the drum 8 for each batch of concrete to be mixed. A suitable valve for the discharge neck 40 will be provided, but for the purpose of this case it is not thought necessary to show the same.

The parts thus far described are of standard and well known construction and have been illustrated simply for the purpose of showing one use of the invention.

Referring now in detail to the invention, which provides timing and dumping mechanism for the drum 8. This mechanism includes pairs of planetary gears 41 and 42. Said gears 41 and 42 of each pair are rigidly connected and loosely journaled on a disk-like head 43 keyed to a short shaft 44, the outer end portion of which is journaled in a bearing 45 on a bar 46 secured to the truck 13.

This shaft 44 is driven from the shaft 22 by a sprocket chain 47 which runs over a relatively small sprocket wheel 48 on the shaft 22 and a relatively large sprocket wheel 49 on the shaft 44.

The transmission mechanism also includes a tubular shaft 50 axially aligned with the shaft 44 with its inner end portion telescoped onto the inner end portion of the shaft 44. The shaft 50 is journaled in a bearing 51 on a bar 52 which extends parallel to the bar 46 and is secured to the truck 13. Formed on the inner end of the tubular shaft 50 is a gear 53 with which the planetary gears 42 mesh.

Loosely journaled on the inner end portion of the shaft 50 is a stop wheel 54 having formed with its hub 55 a gear 56 with which the planetary gears 41 mesh. A sprocket chain 57 runs over a relatively large sprocket wheel 58 on the trunnion 10 and a relatively small sprocket wheel 59 on the outer end of the shaft 50.

On the periphery of the stop wheel 54 is a ratchet tooth 60. Co-operating with the stop

wheel 54 is a horizontal gravity-held latch bar 61 which extends tangentially away from the top of the stop wheel 54 and has its outer end rigidly secured to a pintle 62 loosely journaled in bearings 63 on a housing 64 mounted on a tie bar 65 secured to the bars 46 and 52. On the free or inner end of the latch bar 61 is a detent 66 arranged to be engaged by the tooth 60 on the stop wheel 54 and stop said wheel at a predetermined time. Obviously, the stop wheel 54 and latch bar 61 afford a brake for holding the gear 56.

To support the latch bar 61 and lift the same to move its detent 66 out of engagement with the stop shoulder 60 to release the stop wheel 54, said bar is provided with a crank arm 67 rigidly secured to the pintle 62 and having at its free end a bracket 68 equipped with a roller 69 arranged to run on the periphery of a timing wheel 70. Said wheel 70 is provided with a peripheral notch 71 into which the roller 69 drops at a predetermined time to lower the latch bar 61 and position its detent 66 in the path of movement of the tooth 60 to be engaged thereby and stop the rotation of the wheel 54 and hence the gear 56.

The wheel 70 is keyed to a shaft 72 journaled in the housing 64 and having a worm gear 73 in said housing that meshes with a worm 74 on a shaft 75 and journaled in said housing and a bearing 76 on the bar 46. This shaft 75 is driven from the shaft 44 by a sprocket chain 77 which runs over sprocket wheels 78 and 79 in said shafts, respectively.

The operation of the above described invention may be briefly stated as follows:

To mix a batch of concrete, the proper amount of sand and cement are placed in the skip 30 and said skip raised by operating the shaft 37 from the engine to wind its cables 35 on the drums 36. At the limit of the upward movement of the skip 30 it automatically moves into a dump position, as shown by broken lines in Fig. 1, and discharges its contents into the drum 8. The proper amount of water is also discharged into the drum 8 from the tank 39.

With the proper materials in their exact proportions in the drum 8 the clutch 23 is set to drive the shaft 22 and thereby rotate said drum by the pinion 28 acting on the ring gear 29. At the time the clutch 23 is set the latch bar 61 is held raised by the timing wheel 70 with its detent 66 out of the path of movement of the tooth 60 on the stop wheel 54. The notch 71 in the timing wheel 70 is just forward of the roller 69 so that said wheel will make substantially a full rotation before the roller 69 drops into said notch and thereby allows the latch bar 61 to drop and position its detent in the path of movement of the tooth 60 on the stop wheel 54.

For the purpose of this case it may be assumed that it takes the timing wheel a minute

and one-half to make a complete rotation which will be the time the batch in the drum is mixed.

From the shaft 22, motion is imparted to the shaft 44 by the sprocket chain 47 to cause the planetary gears 41 and 42 to revolve around the axial gears 53 and 56. As previously stated, the axial gear 53 at this time is idle and the axial gear 56 is driven due to the difference in ratio between the planetary gears 41 and axial gear 53 and the planetary gears 42 and the axial gear 56. During this time the timing wheel 70 is being driven by the connections 72 to 79, inclusive. After the wheel 70 has made substantially one complete rotation, its notch 71 is brought into registration with the roller 69 which moves therein and allows the latch bar 61 to drop by gravity to position its detent 66 in the path of movement of the tooth 60 on the stop wheel 54 which is being driven by the axial gear 56. When the tooth 60 engages the detent 66 the rotation of the wheel 54 is stopped and its axial gear 56 becomes a base of resistance for the planetary gears 41 and thereby causes the planetary gears 42 to rotate the axial gear 53 and drive the shaft 50 which, through the connections 57—58—59, rocks the bar 9 and thereby moves the drum 8, while it is being rotated, into a dumping position, as shown by broken lines in Fig. 1. At the completion of the dumping action of the drum 8 the latch lever 14, which has been riding on the periphery of one of the flanges of the wheel 16, drops into the lock notch 15 and holds the drum 8 against the action of the weight 17 to lift the same. This weight 17 has been lifted during the dumping of the drum 8 by the winding of the cable 18 on the flanged wheel 16.

Also at the completion of the dumping movement of the drum 8 the timing wheel 70 has moved into a position to carry its notch 71 past the roller 67 and thereby lift said roller, which in turn lifts the latch bar 54 and moves its detent 66 out of the path of movement of the tooth 60 and releases the stop wheel 54. The operator, at the completion of the dumping action of the drum 8, also releases the clutch 23 and stops further rotation of the shaft 22.

After the batch in the drum 8 has been dumped, the operator releases the latch lever 14 and the weight 17 returns said drum to a filling position. During the return movement of the drum 8 the connections for dumping the drum 8 will be rotated backward, including the wheel 54, and the planetary gears 41 and 42 will rotate on their connections with the head 43. At the completion of the return movement of the drum 8 to its filling position, the dumping connections therefor will be properly reset for the next operation of the machine.

65 What we claim is:

1. In combination with a machine of the character described having a drum mounted for rotary and discharge movements, driving connections for rotating the drum, and automatic means for moving the drum into discharge position at the completion of a predetermined period of time of rotation.

2. The structure defined in claim 1 in further combination with automatic means for holding the drum in discharge position.

3. The combination with a member mounted for rotary and swinging movements, of power-actuated means for rotating the member, a pair of axial gears, a pair of planetary gears meshing with the axial gears, driving connections from the power-actuated means to the planetary gears, the ratio between the planetary gears and the axial gears being such that normally one of the axial gears is idle and the other driven, said idle gear having connections for imparting the swinging movement to the member, timed automatic means actuated from the power means for stopping the driven axial gear and thereby cause the planetary gears to drive the idle axial gear and then release the driven axial gear.

4. The combination with a drum mounted for rotary and dumping movements, of power-actuated means for rotating the drum, a pair of axial gears, a pair of planetary gears meshing with the axial gears, driving connections from the power-actuated means to the planetary gears, the ratio between the planetary gears and the axial gears being such that normally one of the axial gears is idle and the other driven, said idle gear having connections for moving the drum to dumping position, timed automatic means actuated from the power means for stopping the driven axial gear and thereby cause the planetary gears to drive the idle axial gear and then release the driven axial gear.

5. The structure defined in claim 4 in further combination with a latch for holding the drum in a dumping position.

6. The structure defined in claim 4 in further combination with means for returning the drum from a dumping to a filling position.

7. In a concrete mixer of the class described, the combination with a tiltable mixing drum of means for automatically tilting the drum for discharge action after the lapse of a predetermined length of time.

8. A concrete mixing machine of the class described, comprising in combination, a tiltable mixing drum, means for automatically tilting the drum into a discharging position after the lapse of a predetermined length of time, and means for constantly exerting a tendency to return the drum to its non-discharging position.

9. A concrete mixing machine of the class described, comprising in combination, a mix-

ing drum tiltable for discharge purposes, means for automatically tilting the drum to a discharging or dumping position after the lapse of a predetermined length of time, and means for locking the drum in the dumping position.

10. A mixing machine of the class described, comprising in combination, a mixing drum adapted to assume discharging and non-discharging positions; a lock for maintaining the drum in discharging position, and means constantly exerting a tendency to maintain the drum in a non-discharging position; said lock being releasable to permit the drum to assume a non-discharging position.

11. A mixing machine of the class described, comprising in combination, a mixing drum adapted to assume discharging and non-discharging positions and means for automatically causing the drum to assume the discharging position after the lapse of a predetermined length of time.

12. A mixing machine of the class described, comprising in combination, a mixing drum adapted to assume discharging and non-discharging positions; means for locking the drum in discharging position; means constantly exerting a tendency to maintain the drum in a non-discharging position, and means for causing the drum to assume a discharging position, movement of the drum into the discharging position, storing up energy in the means tending to maintain the drum in a non-discharging position to later cause the return of the drum to the non-discharging position.

13. In a concrete mixing machine of the class described, the combination with a mixing drum tiltable for discharging purposes of means for automatically tilting the drum after the lapse of a predetermined length of time; means for returning the drum to a non-discharging position, and means for storing up energy incident to discharging movement of the drum to cause operation of the last named means when desired.

14. In a mixing machine of the class described, the combination with a mixing drum tiltable for discharging purposes, a means for maintaining the drum in a non-discharging position, and instrumentalities automatically operable after the lapse of a predetermined length of time to positively move the drum into a discharging position.

15. In a mixing machine of the class described, the combination with a tiltable mixing drum and means for tilting the drum into a discharging position, of a weight movable incident to movement of the drum into the discharging position to store up energy therein, which is available for later returning the drum into a non-discharging position.

16. In a concrete mixing machine of the class described, the combination with a tiltable mixing drum, of means for automatically titling the drum after the lapse of a predetermined period of time, a weight movable incident to movement of the drum into a discharging position to store up energy therein, which later causes return of the drum to a non-discharging position, and means for locking the drum in discharging position.

17. In a concrete mixing machine of the class described, the combination with a tiltable mixing drum, of means for automatically titling the drum into a discharging position after the lapse of a predetermined length of time; said last named means including planetary gearing normally inoperative, and instrumentalities for bringing the planetary gearing into operation at the expiration of the predetermined period of time; said planetary gearing operating to move the drum into discharging position.

18. In a concrete mixing machine of the class described, the combination with a tiltable mixing drum, of means for automatically moving the drum in a discharging position upon the termination of a predetermined period of time; said last named means comprising differential gearing normally inoperative when all the parts thereof are freely movable, and means for positively preventing rotation of one of the members of the gearing to cause effective operation thereof, and means to automatically cause operation of said last named means after the lapse of the predetermined period of time.

In testimony whereof we affix our signatures.
